UNITED STATES PATENT OFFICE.

NELSON P. JOHNSON, OF SOUTH PASADENA, CALIFORNIA, ASSIGNOR TO THORO POWDERED TOILET SOAP COMPANY, OF LOS ANGELES, CALIFORNIA, A CORPORATION OF CALIFORNIA.

MEASURING AND DISPENSING DEVICE.

1,172,603.

Specification of Letters Patent. Patented Feb. 22, 1916.

Application filed January 2, 1915. Serial No. 106.

To all whom it may concern:

Be it known that I, NELSON P. JOHNSON, a citizen of the United States, residing at South Pasadena, in the county of Los Angeles and State of California, have invented a new and useful Measuring and Dispensing Device, of which the following is a specification.

This invention relates to a measuring and dispensing device, and more particularly to a measuring and dispensing device for dry materials such, for instance, as powdered soap.

One of the objects of the invention is to provide a dispenser of this nature to be manually operated by the hand of the user to discharge thereinto a definite quantity of its contents.

Another object of the invention is to provide a dispenser which will maintain its contents in a very sanitary condition, and one which is without complicated mechanism.

A further object of the invention is to provide a measuring and dispensing device for dry materials which shall be a general improvement over such devices now in use.

With these and other objects in view, the invention consists of certain novel features of construction, combination, and arrangement of parts as will be hereinafter fully described, illustrated and claimed.

Figure 1 is a perspective view showing the dispenser attached to a wash bowl. Fig. 2 is a bottom plan view of the dispenser with the bottom wall removed. Fig. 3 is a top plan view of the dispenser with the body portion of the container omitted. Fig. 4 is a vertical sectional view taken on the plane of line 4-4 of Fig. 3. Fig. 5 is a vertical longitudinal sectional view on a plane at right angles to the plane of Fig. 4. Fig. 6 is a detail fragmentary sectional view taken on the plane of line 6-6 of Fig. 3.

Referring in detail to the drawings by numerals, 1 designates as an entirety the container of the device, which in the present embodiment of the invention, comprises a base 2, body portion 3 and cover 4, all cylindrical in cross section. The body is detachable from the base and is connected thereto by a bayonet joint 4', which permits of easy detachment so that the container may be

quickly cleaned. A partition 5 is provided horizontally within the base 2, and this partition is formed with a discharge opening 6 directly over the opening 7 in the bottom 8 of the container. On the top of the partition 5 is mounted an annular carrier 9 which is formed with an annular series of pockets 10 adapted to be brought into registration with the discharge opening 6 by means of the actuating mechanism. This mechanism comprises shaft 11, which extends through the carrier, and which has rigidly secured to its lower end under the partition 5 a ratchet wheel 12, which may be actuated by a pawl 13 pivoted at one end by means of the fastener 14 to the under side of a flat metal plunger 15. The pawl carries an upstanding tooth 14' to engage the teeth of the ratchet wheel and this tooth is held in engagement with the ratchet wheel by means of a spring 16. The ratchet wheel is so designed and the movement of the plunger 15 is so limited by the pin 16' as to cause the carrier to turn on each actuation of the plunger sufficiently to bring one of the pockets 10 into registration with the discharge opening 6.

The plunger works through openings formed in the base and projects into a hollow arm 17 forming a part of a bracket 18 which may be secured to a suitable support by means of fasteners 19. A spring 15' returns the plunger to its normal position. To prevent the contents of the container caking and lumping, I provide on the upper terminal of the shaft 11 an agitator 20 consisting of a pair of twisted blades as shown.

A continuous discharge of the contents is prevented by the cover plate 21 secured to the interior of the container directly over the discharge opening 6 and above the disk carrier 9. This retaining plate is large enough to cover each of the pockets as they come into registration with the discharge opening, and it is provided with a flat metal spring 22 on its under side, which springs into the pockets as they move over the discharge opening, and forces the contents outwardly. This spring also acts as a brake and prevents the carrier moving except when the plunger is actuated.

When a charge of the container's contents 23, which in the present instance is soap, is

desired, the plunger is forced inwardly. This movement causes the pawl 13 to turn the ratchet wheel 12 sufficiently to bring one of the full pockets of the carrier 9 under cover plate 21 and above the discharge opening. When the pocket reaches this position, the spring 22 flies downwardly and knocks the contents of the pocket out and said contents fall into the operator's hand, as shown 10 in Fig. 1.

From the foregoing description taken in connection with the accompanying drawings, it will be seen that I have provided a very simple and practical measuring and dispensing device, especially adapted for dry materials, and it will be understood that while the drawing shows the preferred embodiment of my invention, minor changes in construction and arrangement of parts may 20 be made without departing from the scope and spirit of the invention as claimed.

What I claim is:

1. In a dispenser, a container having a partition formed therein, the partition and 25 bottom of the container being each formed with a discharge opening one above the other, a carrier mounted on the top of the partition and having pockets adapted to align with the discharge openings, a cover 30 plate positioned over the discharge openings in close proximity to the top face of the carrier, a spring carried by the cover plate to project into the pockets as they move un-

der said plate, and means for intermittently rotating the carrier to bring the pockets into 35 alinement with the discharge openings.

2. A dispenser for dry materials comprising a container having a discharge opening in the bottom thereof, a horizontal partition within said container having a discharge 40 opening above said first mentioned opening, a carrier mounted on the partition having pockets adapted to align with the discharge openings, a plate mounted above the carrier in close proximity thereto, said plate being 45 in alinement with the discharge openings, a spring carried by the plate to project into the pockets as they are moved into registration with the discharge openings, a shaft extending through the partition and being 50 rigidly secured to the carrier, an agitator secured to the shaft above the partition, a ratchet wheel secured to the shaft below the partition, a reciprocatory plunger movable through the container under the partition, a 55 pawl pivoted at one end to the plunger and having a tooth to engage said ratchet wheel, and means for limiting the movement of the plunger in one direction.

In testimony whereof I have hereunto set 60 my hand at Los Angeles, California, this 17th day of December, 1914.

NELSON P. JOHNSON.

In presence of—

RODNEY M. SMITH,
LORO M. BOWERS.
